[57] CLAIM

The ornamental design for a housing for an electrical connector plug, as shown and described.

DESCRIPTION

FIG. 1 is a front elevational view of a housing for an electrical connector plug showing a first embodiment of my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof;

FIG. 7 is a cross-sectional view thereof taken along the line 7—7 in FIG. 6;

FIG. 8 is a front elevational view of a housing for an electrical connector plug showing a second embodiment of my new design;

FIG. 9 is a top plan view thereof;

FIG. 10 is a bottom plan view thereof;

FIG. 11 is a left side elevational view thereof;

FIG. 12 is a right side elevational view thereof;

FIG. 13 is a rear elevational view thereof;

FIG. 14 is a cross-sectional view thereof taken along the line 14—14 in FIG. 13.
